(57) CLAIM

The ornamental design for an aerobic weight, substantially as shown and described.

DESCRIPTION

FIG. 1 illustrates a front view of an aerobic weight.

FIG. 2 illustrates a rear view of the aerobic weight of FIG. 1; and,

FIG. 3 illustrates a top view of the aerobic weight of FIG. 1. The broken line portions of FIG. 1 are for illustrative purposes only and form no part of the claimed design.
